ADVERTISING DISPLAY DEVICE

Frank Dannenberg, John L. Frank, and Archibald Groth, Rochester, N. Y.

Application March 13, 1936, Serial No. 68,762

5 Claims. (Cl. 40—130)

The present invention relates generally to advertising display devices and more especially electrical display devices for use in connection with the dispensing of fluids, such as for instance, beer, in tap rooms and other places, although the invention is capable of employment with other fluids and in other situations.

In connection with the dispensing of beer, however, the invention finds an especial advantage, since it is quite common to have beers of several different makes on tap and an advertising display prominently distinguishable from the usual display cards, is highly to be desired.

For the above reasons the present invention proposes an electrically actuated display sign which will be lighted whenever, and as long as, a particular beer is being dispensed, and while such an arrangement might be controlled from the tap handle of a beer faucet, it is our object to avoid any interference with, or attachment to, the visible portions of the usual dispensing apparatus by employing a control device insertable in the flow line of the fluid which will be in effect whenever the fluid is in movement or, in other words, is being dispensed.

Moreover it is a further consideration not only to actuate the advertising display or sign whenever the fluid is being dispensed, but to make this actuation intermittent throughout the entire dispensing period.

With the above in mind the invention resides in the various features and apparatus to be now described in detail in connection with the accompanying drawing which forms a part of this specification, and in which,

Fig. 1 is a side view of the fluid actuated controlling device.

Fig. 2 is a sectional view taken longitudinally therethrough.

Fig. 3 is a side view, partially broken away and in section.

Fig. 4 is a detail section taken on the line 4—4 of Fig. 2, and

Fig. 5 is a plan view, in part diagrammatic, illustrating the complete display apparatus.

Referring now to these figures, there is shown in Figure 5 an apparatus including a display sign in the form of a light box 10, the transparent or translucent front plate 11 of which may have imprinted, painted or otherwise fashioned thereon the name of the beer or fluid to be displayed. Within this box is suitably mounted an electrical lighting bulb 12 included in an electrical circuit, one of the wires 13 of

which is connected to a battery or other suitable source of current 14 having a wire 15 extending therefrom and connected to a stationary contact member 16.

The contact member 16 cooperates with a rotatable switch member 17 to which a wire 18 from the lighting bulb 12 is connected. This switch member 17 presents a segmental contact 19 to the stationary contact member 16 and is otherwise insulated therefrom, so that member 17 during each revolution by reason of the flow of fluid past the same, completes the lighting circuit while the contact 16 rests on segment 19. Thus during continuous rotation of member 17 the light in box 10 will be alternately flashed and darkened so that the intermittent action will attract and draw attention to the display sign and make it known that the named beer is being drawn.

For the above purposes, the rotatable switch member 17, is mounted, as shown in Figures 1 to 4 inclusive, in a casing 20 so that its peripheral channel 21 extends into a fluid passage 22 of the casing. The channel 21 is divided into an annular series of fluid compartments by reason of radial division plates 23 and these compartments open adjacent to a serrated portion 24 of the wall of the fluid passage 22 so that during movement of fluid through the channel, the member 17 will be forced to rotate.

The fluid passage communicates at its opposite ends with threaded bores of the casing designed to receive the threaded ends of portions 25, 26 of the pipes forming the beer line, and the shaft 27 upon which member 17 rotates is supported partly in the casing 20 and partly in a plug 28 threaded into and closing one side of the casing. The plug 28 carries the contact 16 and for this purpose has an insulating sleeve 29 with a stem 30 at its outer end for receiving wire 15 and to form an abutment for a spring 31 which presses contact 16 into engagement with the adjacent face of member 17 which is insulated except for the segment 19. Thus wire 18 may be connected as desired to the casing 20 and current will pass to the member 17. When the latter rotates the lighting circuit will be completed whenever the contact 16 engages segment 19 and thus the light will be lighted between periods of intermittent action thereof about as often as it will remain unlighted.

The important point of the operation is, however, the fact that during the flow of fluid through the switch the light will be flashed on and off and attention forcibly directed to the

display sign for this reason. A second importance results from the fact that by controlling the light by reason of the flow of fluid through the supply line, it is unnecessary to mutilate or 5 in any way add to the normally visible control parts of a beer or other tap.

What is claimed is:

1. In a device of the character described for use with a fluid conduit, a circuit controller including a casing for connection in said conduit, said casing having pipe receiving bores and a fluid passage between said bores, a rotatable member in said casing having a channeled partitioned peripheral portion extending into said 15 passage, said member having a contact segment, and a contact member supported in connection with said casing for engaging said segment during rotation of said rotatable member.

2. In a device of the character described for use with a fluid conduit, a circuit controller including a casing for connection in said conduit, said casing having pipe receiving bores and a fluid passage between said bores, a rotatable member in said casing having a channeled partitioned peripheral portion extending into said 25 passage, said member having a contact segment, and a contact member supported in connection with said casing for engaging said segment during rotation of said rotatable member, the wall 30 of said passage being serrated along a portion thereof adjacent to said rotatable member.

3. A circuit controlling member for use in fluid conduits, comprising a casing having pipe receiving bores and a fluid passage between said bores, a plug threaded into one side of said casing and having an insulated contact member, a 35 rotatable member supported in the casing and plug and having a radially bladed periphery extending into the fluid passage to rotate the same 40 by moving fluid, said rotatable member having an insulated side wall provided with a segmental

contact element for engagement, during rotation thereof, by the said contact member.

4. A circuit controlling device for use in connection with fluid conduits, comprising a casing having pipe receiving bores at spaced-apart points and a fluid passage between said bores, a plug detachably associated with said casing at one side and having an insulating sleeve there-through, a spring-pressed contact member in said sleeve, a rotatable member having an axial shaft 10 supported by the casing and plug and having its periphery extending into said passage and provided with means to rotate the member during flow of fluid through the passage, said rotatable member having an insulated side wall 15 adjacent said contact member, and a contact element in said side wall for engagement by said contact member during each rotation of the rotatable member.

5. An advertising display device for use in connection with the dispensing of fluids from a fluid conduit, comprising a sign, means forming a lighting circuit for the sign, and a circuit controller in said circuit including a casing for connection in said conduit, having pipe receiving bores and a fluid passage between said bores, a rotatable member in said casing actuated by the flow of fluid through said passage when the fluid is in movement in the conduit, said rotatable member having a contact segment connected to the lighting circuit, and a contact member also, connected to the lighting circuit and supported by the casing for engagement with said contact segment during rotation of said rotatable member whereby the lighting circuit will be alternately completed and broken continuously during movement of fluid in the conduit. 20 25 30 35
